(57) CLAIM

The ornamental design for a shoe upper, as shown and described.

DESCRIPTION

FIG. 1 is a front perspective view of a shoe upper showing my new design;

FIG. 2 is a rear perspective view thereof; and,

FIG. 3 is a lateral side view thereof.

The broken line showing that is immediately adjacent to the two forward end of the front shaded area, and the broken line that is immediately adjacent to the rearward end of the rear shaded area represent unclaimed boundaries of the design. The broken of the remainder of the shoe is for environmental purposes only and forms no part of the claimed design.
